GARMENT BAGGING APPARATUS

Charles S. Allen, Bakersfield, Calif.

Application October 19, 1937, Serial No. 169,872

4 Claims. (Cl. 226—18)

This invention aims to provide novel means whereby an operator can raise or lower a bag, to uncover or cover a garment, it being a matter of common knowledge that when garments come from a cleaner's establishment, the user prefers to keep them in a bag.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

20 In the accompanying drawing:

Fig. 1 shows in elevation, a device constructed in accordance with the invention;

Fig. 2 is a top plan of the cross arm and attendant parts;

25 Fig. 3 is a side elevation showing the suspension rod, the cross arm and attendant parts;

Fig. 4 is a top plan of the clip that holds the bag, the suspension rod being in section.

In the ceiling 1 of a closet, or in any other suitable elevated place, is mounted a hook 2 which is 30 detachably engaged with a hook 3 on the upper end of a suspension rod 4, which may be a piece of wire, the suspension rod being supplied at its lower end with an eye 5 detachably engaged with 35 a hook 6 on a hanger 7 of any desired and common form, the hanger being adapted to carry a garment 8.

A cross arm 9 is secured to the suspension rod 4, near to the upper end of the suspension rod, 40 and is of plate-like form, the cross arm having backwardly extended ears 10 in which are mounted round-edged grommets 11 which will not fray a flexible element or cord 12 which is rove slidably through them, the flexible element being supplied at one end with a handle 14.

The numeral 15 marks a resilient pinch clip or holder, adapted to engage an open-bottomed bag 21, the pinch clip being released by arms 16 and being of ordinary construction, the arms having 50 holes 17. One end of the flexible element 12 is formed into a first loop 18 engaged through the holes 17 in the arms 16, the flexible element being knotted at 19 to form a laterally extended second loop or guide 20, slidably mounted on the suspension rod 4. With the parts arranged as

shown in Fig. 1, the operator eases off on the flexible element 12, the flexible element runs through the grommets 11, and the bag 21 descends, the bag receiving and covering the garment 8.

One of the reasons for having the second loop or guide 20, engaged slidably with the suspension rod 4, is to keep the bag 21 in proper place, so that when it moves downwardly, it will receive and cover the garment 8. Another reason for 10 having the second loop or guide 20 is that if the pinch clip 15 is detached from the bag 21, and, especially, if the flexible element 12 happens to be located with respect to the cross arm 9 so that each portion of the flexible element 12 is of considerable length, the parts of the flexible element 15 will tend to become entangled with each other and with the suspension rod 4.

When the operator desires to use the garment 8, all that he has to do is to haul on the flexible 20 element 12, by means of the handle 14, the bag 21 being raised to the position shown in Fig. 1, and the garment 8 being exposed.

Having thus described the invention, what is claimed is:

1. In a device of the class described, a suspension member having means at its upper end for engaging a support and having means at its lower end for carrying a garment hanger, a flexible element, means on the suspension member 30 for carrying the intermediate portion of the flexible element slidably, a bag holding pinch clip having arms provided with openings, one end of the flexible element being formed into a loop engaged through the openings, and the loop being 35 extended to form a guide slidably mounted on the suspension member, the opposite end of the flexible element being under the control of an operator.

2. In a device of the class described, a suspension member having means at its upper end for engaging a support and having means at its lower end for carrying a garment hanger, a flexible element, means on the suspension member for carrying the intermediate portion of the flexible element 40 slidably, a bag holding member having an opening, one end of the flexible element being formed into a loop engaged through the opening, and the loop being extended to form a guide slidably mounted on the suspension member, the opposite end of the flexible element being under 45 the control of an operator.

3. In a device of the class described, a suspension member having means at its upper end for engaging a support and having means at its lower 50

end for carrying a garment hanger, a flexible element, means on the suspension member for carrying the intermediate portion of the flexible element slidably, a bag holding member having an opening, one end of the flexible element being formed into a loop engaged through the opening, and the loop being knotted together, intermediate its ends, to form an eye slidably mounted on the suspension member, the opposite end of the flexible element being under the control of an operator.

4. In a device of the class described, a cross arm provided near its ends with backwardly extended ears, grommets mounted in the ears, a

flexible element slidable through the grommets, one end portion of the flexible element being under the control of an operator, bag engaging means carried by the opposite end portion of the flexible element, a suspension member secured to the rear surface of the cross arm, between the ears, the suspension member having means at its upper end for engaging a support and having means at its lower end for carrying a garment hanger, and the grommets being set back far enough so that when the flexible element slides through the grommets, the flexible element will be out of contact with the suspension member.

CHARLES S. ALLEN.
